UNITED STATES PATENT OFFICE.

JOHN W. ASHWORTH, OF NEW YORK, N. Y.

ADVERTISING DEVICE.

Application filed February 24, 1926. Serial No. 90,313.

This invention is an advertising device and the object of the invention is to provide novel and highly attractive means for displaying advertising matter in such a way 5 as to command attention.

The present invention while essentially an advertising medium has the further function of forming a support for apparatus such as a weighing scale for use in groceries, 10 butcher stores and other environments and when so used serves to maintain the scales or other apparatus free from dust, etc.

In its preferred practical form, the invention embodies a suitable hanger on which 15 a supporting frame is mounted for free rotation. The supporting frame is provided with suitable vanes against which air is adapted to be impelled by a motor driven fan carried by the hanger in order that 20 through the operation of such air upon the blades, the displacement carrying frame is caused to revolve. In practice, a second fan is also generally associated with the one already mentioned for impelling a draft of 25 air downwardly over scales suspended from the hanger, for the purpose of keeping flies off of the scales when the device is used for example, in butcher shops. The rotary frame, which serves to support the signs is

30 a novel and unique construction, that portion below the blades preferably being opaque and surrounding the source of illumination contained within the lower portion of the frame, so that the light from said 35 source of illumination is transmitted through opaque signs. The blades are, moreover, preferably at least in part, of glass, and the light shining upwardly through the blades is adapted to illuminate exteriorly advertising signs carried by the upper portion of 40 the frame. This is a pronouncedly novel feature and the optical effect is highly pleasing and particularly striking. It commands attention especially when the glass of the 45 blades is multi colored as is generally the case in the practical form of the invention.

In practice, scales are generally suspended from the hanger below the revolving frame, although it is within the purview of this 50 invention to support any suitable platform or article from the hanger.

Features of the invention, other than those specified, will be apparent from the herein-after detailed description and claims, when

read in conjunction with the accompanying 55 drawings.

The accompanying drawings illustrate one practical embodiment of the invention, but the construction therein shown is to be understood as illustrative, only, and not as 60 defining the limits of the invention.

Figure 1 is a vertical section of the device partly in elevation.

Figure 2 is a section on the line 2—2 of 65 Figure 1.

Figure 3 is a section on the line 3—3 of Figure 1; and,

Figure 4 is a section on the line 4—4 of Figure 1.

Referring to the drawings, 1 designates a 70 suitable hanger secured at its upper end to an appropriate fixed support and preferably in the form of a hollow metal tube or pipe. To the lower end of this hanger is rigidly secured a stirrup 2 bound to the hanger by 75 a nut 3, so that the stirrup is locked to the hanger against rotation.

Supported in the stirrup is an electric motor 4, the armature shaft 5 of which extends in an upward direction and has secured thereto two fans 6 and 7. Between the fans extends a partition 8 and about the respective fans are skirts or baffles 9 and 10 to preclude interference between two fans. It will be noted in Figure 1 that these fans 85 are of reverse pitch; that is to say one is right handed and the other left handed.

Current is fed to the motor 4 through wires 11 and 12 which are led downwardly through the hanger 1 and thence to the motor. The wire 11 includes a rheostat 13 by which the speed of the motor may be regulated and the wire 12 includes a switch 14 for controlling the feed of the current to the motor.

Superimposed on the bracket and surrounding the hanger 1 is an antifriction bearing 15 on which rests a plate 16. To this plate 16 are attached a number of metal straps 17 which extend radially outward for 100 a distance, then downwardly in parallel relation and then inwardly so that at their lower-extremities, they form inturned feet 17a. Six of such straps are shown in the drawings. They are all anchored at their tops by attaching them to the plate 16 and at their bottoms they are all anchored to an annular plate 20 provided at its outer pe-

riphery with an upstanding flange 21 (see Figure 1). Encircling the straps 17 adjacent the tops of the vertical portions thereof is a hoop 22 and a similar hoop 23 encircles the straps at the bottoms of such portions. The hoops are circular and serve to properly space the straps annularly and at the same time serve the function of maintaining proper curvature of display cards adapted to be supported on the frame which I have thus far described.

Three of these show cards designated 24 are shown in Figure 3, although these cards are removed in the showing of Figure 1. To hold the cards in place, their lateral edges are adapted to be introduced behind vertical strips 25 which extend parallel to and overlie every alternate one of the straps 17, and are secured in spaced relation thereto in any suitable way.

The lateral edges of each card are introduced behind the strips 25, while the lower edges of each card rest on the plate 20 inwardly of the flange 21. In practice, the cards 24 are preferably of translucent material, so that they may be interiorly illuminated by means of lamps 26 which are supported on the bracket 27 clamped between the nut 3 and the stirrup 2, as clearly shown in Figure 1.

Current may be fed to the lamps in any suitable way not shown. Secured in accurate spaced relation about the upper hoop 22 are the lower ends of three upstanding channel bars 27, the upper ends of which are bent inwardly at an angle and are secured to a plate 28 which loosely surrounds the hanger 1. A cover plate 29 rests on top of the bars 27 and is preferably of the ornate configuration shown in Figure 2, although not necessarily so. By constituting the bars 27 of channel shape, it is entirely practical to support three cards 30 in the manner shown in Figure 2, wherein it will be noted that the lateral edges of each card engage with the corresponding channel bar 27 in order to hold the cards in position. As shown, these cards are flexed when held in the manner described so that their exterior surface is concave.

It will thus appear that the plate 16 mounted on the antifriction bars 15 serves to support the bars 27 with the signs 30 and the straps 17 with the various other parts 55 and the display cards mounted thereon. These parts which are mounted for rotation on the antifriction bearing constitute a revolvable frame to which rotation is adapted to be imparted by means of a blast of air forced upwardly by the fans 6. To provide for this rotation under the impulse of such air, the horizontal portions of the straps 17 carry blades inclined in such manner as to cause rotation of the entire frame when the blast of air impinges said blades. Each

blade embodies an upwardly extending portion 31 and a downwardly extending portion 32 and they are bent at such inclination as will produce the proper turning moment at the desired speed. I find it highly practical to form these blades as a frame and in each frame mount colored glass 33.

With this arrangement, light from the lamps 26 will illuminate the translucent advertising cards 24 interiorly and said light will also pass upwardly through the blades 31 and 32 and exteriorly illuminate the upper show cards 30 in colors. The optical result is very striking since the movement with the color cannot pass unobserved.

The invention may be used in any environment purely for display, but in one of its preferred practical forms, the stirrup is provided at its bottom with a hook or eye 34 which serves to support a scale 35. When the device is in operation, the fan 7 will direct a downward blast of air over the scale and serve to keep the flies off the same. This feature of the invention is particularly useful in butcher shops, delicatessen shops and the like.

The invention is not, however, limited to use in combination with a scale, but any suitable article or apparatus may be hung therefrom in place of the scale.

I wish to point out particularly that the advertising matters on the upper portion of the revolving frame are externally illuminated while the show cards at the lower portion of the frame are internally illuminated. It should also be noted that the two fans direct blasts of air in opposite directions. This is the preferred form of the invention, but it is within the purview of the invention to eliminate the fan 7.

The drawings show the invention in the preferred practical form, but it is to be understood as fully commensurate with the appended claims.

I have shown in the drawings, two fans 6 and 7 one of which is right handed and the other of which is left handed, so that when the fans are simultaneously operated, a blast of air will be driven in an upward direction and another blast of air will be driven in a downward direction. I have also explained that the lower fan 7 may, if desired, be omitted. It is also within the purview of this invention to dispense with the fan 7 and with the partition 8 and the skirts 9 and 10 and to make the pitch of the fan 6 of such direction that instead of forcing a blast of air upwardly through the vanes or blades 31 and 32, this draft of air may be forced downwardly, so that the rapid intake of air to the fan through the blades or vanes will impart rotation to the frame and such draft will be directed downwardly from the fan over the scale. Manifestly, this slight change in operation may result

in rotation of the frame in an opposite direction from the construction, as shown in the drawings, but, in practice, this is not material.

5 I have referred to the speed of rotation of the frame as being governed by the speed of the motor which is controlled by a suitable rheostat. I may, in practice, however, dispense with this rheostat, since the speed of 10 rotation of the frame depends upon the pitch of the blades or vanes 31 and 32. Since these vanes are more or less pliable, they may be manually adjusted by bending them slightly in one direction or the other to 15 vary their pitch and in this way, the speed of operation of the frame may be changed and determined as may be desirable.

Having thus fully described the invention, what I claim as new and desire to secure 20 by Letters Patent is:

1. In an assembly of the character described, a frame mounted to rotate and embodying a plurality of blades, a motor driven fan positioned to force a blast of air 25 against said blades in a direction parallel to the axis of rotation of said frame to revolve the frame, a source of illumination within said frame, translucent advertising cards carried by the frame and adapted to 30 be interiorly illuminated from the source of illumination, and additional advertising cards carried by said frame and adapted to be illuminated exteriorly from said source of illumination.

35 2. In an assembly of the character described, a frame mounted to rotate, translucent advertising cards carried by a portion 40 of said frame and forming an inclosure, illuminating means positioned within said inclosure for illuminating said cards interiorly, additional advertising cards carried by another portion of the frame and adapted to be exteriorly illuminated by said illuminating means, a plurality of colored translucent vanes mounted on the frame and positioned between the illuminating means and 45 said additional cards to effect a coloring of the light rays which impinge said cards, and a motor driven fan for directing a blast of air against said blades for the purpose of 50 revolving the frame.

3. In an assembly of the character described, a frame mounted to rotate, translucent advertising cards carried by a portion 55 of said frame and forming an inclosure, illuminating means positioned within said inclosure for illuminating said cards interiorly, additional advertising cards carried by another portion of the frame and adapted to be exteriorly illuminated by said illuminating means, a plurality of colored translucent vanes mounted on the frame and positioned between the illuminating means and 60 said additional cards to effect a coloring of the light rays which impinge said cards, and 65

a motor driven fan for directing a blast of air against said blades for the purpose of revolving the frame, said fan being positioned within and concealed by the said inclosure.

4. In an assembly of the character described, a hanger fixed against rotation, a motor supported by the hanger, a frame supported by the hanger for free rotation thereon, a plurality of vanes carried by the frame, a fan operated by the motor to direct a blast of air against the blades to rotate the frame, advertising cards carried by the frame, means for illuminating the said cards, a scale supported by the hanger, and 75 an additional fan also operated by the motor to direct a blast of air upon the scales.

5. In an assembly of the character described, a hanger supported against rotation, a stirrup suspended on the hanger, a motor carried by the stirrup and having a fan operable by said motor, a source of illumination carried by the hanger within the frame, 80 a series of vanes positioned in the path of the blast of air from the fan for causing rotation in the frame, advertising matter carried by the frame to be interiorly illuminated from the source of illumination, and additional advertising matter carried by the frame and adapted to be illuminated exteriorly from the source of illumination.

6. In an assembly of the character described, a hanger mounted against rotation, a stirrup supported by the hanger, a motor carried by the stirrup, a pair of fans of opposite pitch operable by the motor, and a scale supported by the hanger in combination with a frame mounted to rotate on the hanger and having translucent blades positioned in the path of air from one of the 100 fans to impart rotation to the frame, a source of illumination carried by the hanger, advertising matter also carried on the frame and adapted to be illuminated from the source of illumination.

7. In an assembly of the character described, a supporting member, a frame mounted on the supporting member for rotation, a plurality of advertising cards carried by the frame, means for illuminating said cards a plurality of vanes mounted on 105 said frame, and a motor driven fan also carried by said supporting member for directing a blast of air against the blades to rotate the frame.

8. In an assembly of the character described, a frame mounted to rotate on a vertical axis and having a plurality of vanes, advertising cards carried by the frame, means for illuminating said cards, a motor driven fan mounted to operate coaxially with the frame for directing a blast of air against the vanes to rotate the frame, and a support on which both the frame and fan are mounted in superimposed relation.

- 9: The combination of a member mounted to rotate on a vertical axis and embodying a plurality of radially extending deflector vanes, and a motor driven blower positioned
- 5: to impel a blast of air in a direction coaxial of said member and against the vanes thereof for the purpose of imparting rotation to said member, said member being shaped to de-

flect the blast of air laterally and to distribute it in a lateral direction whereby circulation of air is set up laterally of the device and in the vicinity thereof.

In testimony whereof I have signed the foregoing specification.

JOHN W. ASHWORTH.
